Attala

UNITED STATES PATENT OFFICE

HOMER T. DARLINGTON, OF WEST CHESTER, PENNSYLVANIA, ASSIGNOR, BY MESNE ASSIGNMENTS, TO OIL CORPORATION OF AMERICA, A CORPORATION OF DELAWARE

APPARATUS FOR THE PRODUCTION OF LUBRICATING OIL

Original application filed May 28, 1927, Serial No. 194,282. Divided and this application filed September 10, 1928. Serial No. 304,859.

An object of my invention is to take out of the oil during the process of manufacture carbon more readily separable to the end that there will be less carbon to deposit, and, 5 therefore, less deposited while the oil is being used as a lubricant.

An object of my invention is to produce a lubricating oil less liable to deterioration under conditions of use than any now available. Another object of my invention is to remove from the lubricating oil during its manufacture, or stabilize in it, component parts of it of minor value as lubricants, which tend to cause deterioration.

15 Another object of my invention is to produce a lubricating oil of low volatility and superior pouring quality; that is, having a low pour test. Another object of my invention is to provide a means for producing 20 standardized lubricating oils of definite, predetermined quality and character as a direct result of distillation and allied operations without subsequent manipulation.

Another object of my invention is to produce 25 lubricating oil of the character and in the manner stated from deteriorated oil, such as oil drained from automobile crank cases, and those qualities and kinds of petroleums that are usually deemed unfit for 30 the purpose.

Another object of my invention is to provide an apparatus that can be readily and effectively used in the practice of my said processes.

35 It is well known that lubricating oil when used where it is subjected to heat approaching its volatilization point is darkened by the formation of carbon within the oil. This is particularly true of oils used in bearings, 40 and is frequently observed with respect to automobile crank case oil. It is also a matter of common knowledge that lubricating oils when volatilizing leave substantial deposits of carbon on the walls of automobile 45 and other explosive engines.

Lubricating oil used in machinery lubrication where it is in continuous contact with moving metal loses some of its lubricating power. This decrease in lubricating value 50 is, I believe, the result of changes in the

oil due to contact with the metal and to frictional heat evolved not only by the movement of the metal parts, but also and perhaps primarily by the movement of the molecules within the oil itself. My observation and 55 experience convinces me that this deterioration in lubricating oil is to a large extent due to cracking during such use; that the change is confined to certain relatively unstable fractions of the oil, the major part 60 of the lubricant remaining unchanged.

In the distillation of lubricating oil stocks, as usually done, these minor constituents which materially limit the useful life of the lubricant distill and condense with the more 65 useful and desirable constituents. I have found that I can treat lubricating oil stock prior to or during distillation with certain colloidal or quasi-colloidal materials, and by holding them dispersed through the oil 70 during distillation or other treatment remove or hold back and prevent the volatilization in large part of constituents undesirable in lubricating oil, and particularly of free or easily separated carbon.

In carrying out the art of my invention, I take lubricating oil that has been used, or crude oil, or heavier fractions thereof, or residue, or mixtures of some or all of them, and intimately commingle the oil stock thus 80 provided with colloidal or quasi-colloidal material, such as bentonite, bentonite and water, hydrated lime, sponge iron, siliceous residue of acid treated clay or serpentine, or mixtures of salt water and clay, or colloid 85 material having metallic coatings, all of which materials or mixtures thereof are hereinafter, for convenience sake, referred to as adsorptive addition agents.

I maintain the colloid addition agent in 90 suspension and incorporation in the oil and desirably colloidally dispersed by mechanically induced circulation and agitation, while I heat it to a temperature above that at which I subsequently distill it. The temperature 95 I so use may vary and may be any temperature between 500° and 850° Fah., both inclusive, and I may carry out the treatment at normal or higher pressure, either in the same vessel or apparatus in which I subse- 100

quently distill, or in a separate vessel or apparatus, subsequently transferring to the distilling unit.

I may at any desired point in the process remove by settling or filtration any of the 5 colloid addition agent, and may repeat the treatment with other colloidal addition agent. I may also at any time remove carbon that has settled out, and I may also before the 10 volatilization of the lubricating oil remove such lighter products as are separated by the preliminary treatment.

By this pre-treatment, which is preferably performed under super atmospheric pressure 15 and at a temperature which will vaporize the more volatile constituents without vaporizing the major portion of the oil stock, I not only remove from the oil stock the free carbon and that which is more readily dissociated, but 20 I vaporize and, as a rule, remove some components of my materials which are more volatile, and I stabilize others by combinations effected when carbon is disassociated, as already stated. Thus I render the lubricating oil subsequently formed from material 25 so treated less likely to form and deposit carbon. I also decrease the volatility of such lubricating oil and minimize it to an appreciable degree to the deteriorating effects 30 of the conditions under which it is used.

One deteriorating influence of considerable importance in the use of lubricants is the dust and dirt, and the fine particles of metal ground from bearings that find lodgment in 35 the oil. These, as has already been intimated, attack certain components of the oil and cause deteriorating changes in them. By dispersing colloid addition agents in the oil stock during pretreatment, I subject it to 40 conditions akin in effect, though they may differ in the characteristics, to those prevailing when the lubricating oil is in actual use, and removing or transforming those components that readily deteriorate, I thus reduce to a 45 minimum the possibility of the oil deteriorating in actual use. The colloidal addition agent in connection with the heat treatment may be employed to coagulate colloidal carbon usually found in still residues and heavy 50 oils. The change of state causes the oil to evaporate at lower temperatures and results in larger proportionate production.

There are usually in petroleum hydrocarbon compounds which when they remain, 55 as they usually do, in lubricating oil, form gums and resins which when the oil is used as a lubricant are deposited on bearings and other parts and are very objectionable. I have found that air or oxygen charged into 60 heated oil stock containing a dispersed colloid addition agent acts upon the gum—and resin—forming compounds in such manner, apparently by oxidation, that thereafter 65 objectionable gums and resins are not formed or deposited, and I have found that the

charged air or oxygen works this change satisfactorily and adequately only when the oil is heated and when colloid agents are also present.

Having removed, held back or transferred 70 the undesirable constituents in my lubricating stock in the manner set forth, I proceed to evaporate and fractionally, or selectively condense such portions of the lubricating stock as I may desire. I may or may not 75 add fresh colloid addition agent to the oil before or during distillation, and generally I prefer to do so. I also preferably, though not invariably, use heat for vaporizing lower 80 than that used in the first treatment, so that any material held by the colloidal addition agent will not break up chemically and their products be found in the fractions condensed.

To accomplish distillation at a low tem- 85 perature, I heat, distill and condense in a vacuum. I am aware that distilling and otherwise treating oil in vacuum is old and well known, and has been practiced in the art for many years. I prefer to use a vacuum 90 such as has been used in actual practice for many years as distinguished from a theoretical vacuum or one that might be practical in laboratory work, but not under actual 95 productive working conditions. I do not, however, restrict myself to a vacuum of any particular degree.

Other features of my process will be made clear in connection with the description 100 which follows of an apparatus which I have invented for use in practicing this process. While this apparatus is peculiarly adapted to the process, its use is not confined to the process, and the process may be performed with any apparatus adapted or adaptable to 105 its various operations.

In the drawing:

A suitable combination of apparatus is shown somewhat diagrammatically.

This is a division of my pending applica- 110 tion, Serial No. 194,282, filed May 26, 1927, for process and apparatus for the production of lubricating oil.

Reference Figure 2 shows a chamber in 115 which oil stock, together with one or more colloid addition agents, is agitated and mixed by paddle 5 and thoroughly commingled. The oil stock and the colloid addition agent or agents are introduced to the chamber 2 through the pipe line 1, or the like, by a pump (not shown) or by other suitable means, and are circulated for heating by a pump 4 through the coils 3 located in a furnace as shown, or by any other suitable means. 7 is a settling chamber with which the chamber 2 is in communication by a pipe line 6. It is provided with means for drawing off carbon 8 and with a valve controlled outlet for vapors 9.

12 is a second mixing chamber, which I 130

call a colloid mixer, connected by the transfer line 11 with the settling chamber 7. It has a stirrer of any suitable type, shown as a paddle 13, and also has valve controlled means 14 for the optional introduction of additional colloid agent. The settling chamber also has valve controlled means 10 for introducing air for treating gum and resin forming compounds.

16 is a vaporizer in communication by the valve controlled pipe line 15 with the mixing chamber 12. It contains distribution plates 21 to provide extensive vaporizing surfaces, and has in connection with it a tubular circulator including a pump 19, or other suitable means of circulating liquids from it at a point below the variable liquid level therein 22 through the coil 18 heated by a furnace as shown, or other suitable means, and returning the liquid to the vaporizing chamber 16 at a point above said distribution plates 21.

A pipe or similar means 1' for the introduction of oil stock and colloid addition agent is provided intermediate the pump 19 and the heating means 18. Valve controlled means 17 is provided for removing carbon and sedimentary deposits, and a pipe or the like 10' is provided for the introduction of air for heating gum and resin forming compounds when oil stock that has not been pre-heated is used, and an agitator 34 for use when addition agent is introduced to the vaporizer 16 through the means 1'.

The vaporizing chamber 16 is connected by suitable vapor outlet means 23 to a controlled selective dephlegmator 24. This dephlegmator 24 contains selective separator plates 26 of such number as may be desired, and pipes or the like 25 and 25' for the selective withdrawal of condensate, two or more in number, according to the number of cuts in finished products desired. The withdrawal pipes 25 and 25' are each controlled by a valve, which may in turn, if desired, be thermostatically controlled.

Connected with the dephlegmator 24 by connections 27 and 28 are a mercury vapor pump, or an inspirator 29, and any other suitable means 30 for creating a vacuum, with a valve controlled pipe 31 for discharging remaining gaseous material, and optionally additional means for cooling 32 with an outlet 33 for water may be provided at any desired point. In practical operation and preferably under super atmospheric conditions, as before stated, I introduce oil stock which it is desired to treat intermixed with one or more colloidal addition agents (as already defined) through 1 into chamber 2 and immediately pass the mixture through the pump 4 and the heating coils 3 and, after raising it to the desired temperature, return it to the chamber 2 where it is thoroughly stirred and commingled. Ordinarily the mixture is circulated for heating only once, but the

operation may be repeated one or more times if deemed desirable or necessary.

From the chamber 2 the mixture passes through the pipe line 6 to the settler 7. It is left there for a sufficient time to permit sedimentary matter to precipitate, and I may draw off heavier sedimentary deposits through the pipe 8, provided for that purpose. I may and, if the oil stock used contains appreciable amounts of gum and resin forming compounds, I do admit air through the pipe 10 to the settling chamber 7 to treat such compounds. The heating of the oil stock in the coil 3 is made sufficient to drive out from the body of the oil lighter constituents and to crack more easily decomposed fractions, and as my purpose is to remove such of these as are not by treatment in the chambers 2 and 7 rendered stable, I may and ordinarily do remove them from the settling chamber 7 through the pipe 9.

The remaining oil stock with the dispersed colloidal addition agent I pass through the pipe line 11 to the mixer 12. If, as happens when some oil stocks are used, the quantity of carbon deposited or coagulated with the colloidal addition agent has been such that enough active carbon free colloidal addition agent is not left in the oil stock to effectively treat it, I may introduce more colloidal addition agent to the oil in the mixing chamber 12 through suitable pipe or other means 14, and I thoroughly disperse the agent so added and any already in the oil by the agitating means 13 provided for the purpose. From the chamber 12 I pass the oil stock with dispersed colloidal addition agent through the pipe line 15 to the vaporizer 16.

The treatment up to this point I designate pretreatment. For it I may substitute operations accomplishing similar results or other operations for preparing the oil stock in any manner deemed desirable, or I may under some conditions and using some kinds of oil stock charge the oil stock into the vaporizer without any pretreatment other than the dispersion in it of colloidal addition agent.

I may cut out, either by the valve in line 15, or by dispensing with it entirely, all or any part of the apparatus 1 to 15, both inclusive, anterior to the vaporizer 16, and may accomplish such dispersion and any other pretreatment by any means and with any apparatus that may be available, or that under conditions then prevailing may be deemed suitable. In that case, I introduce oil stock with colloidal addition agent through the pipe line 1' at a point intermediate the pump 19 and heating coil 18 and under vacuum agitate the oil stock with added addition agent by a paddle 34 or other suitable means.

In every case I circulate the oil containing the colloidal addition agent from the vaporizer 16 or the point of admission 1' 13.

through the heating coils 18 and thence into the vaporizer in such manner that the oil will spread itself over the distribution plates 21 as it falls into the main body of oil, which 5 has a variable level 22. Moisture and entrained oil which separates out of vapors as they pass upward in the vaporizing chamber 16 also drop back onto the distribution plates 21 and into the main body of oil. The vapors 10 from the vaporized 16 pass through transmission means 23 to the dephlegmator 24 for cooling and separation.

I prefer to use a dephlegmator placed horizontally or nearly so and equipped with means 15 for regulating and controlling the rate and degree of cooling and for dephlegmating and separating products selectively. I have invented a dephlegmator peculiarly effective and easily adapted for so selectively dephleg- 20 mating and separating products for which an application for Letters Patent of the United States, Serial No. 186,459 is now pending. While I prefer to use this dephlegmator, any 25 means of cooling and separating that will admit of separating lubricating products of varying distinctive characteristics independently and selectively may be employed.

I will, however, now outline some of the 30 features of any dephlegmator or kindred apparatus which I deem desirable to accomplish the desired purpose and which differentiate it from those heretofore used. In the first place, the dephlegmator should have as 35 many communicating zones or sections progressively arranged as there are distinctive products or "cuts", so-called, to be made, and each side section or zone should have means for withdrawing the product thereof. In the drawing, I have, for purposes of illustration, 40 divided the dephlegmator 24 into two sections or zones by division plates 26 and have provided an outlet 25 and 25' for each zone or section.

Means should also be provided for pro- 45 gressive positive accelerated cooling to the end that there may be essential differences between the lubricating oil produced in the several sections or zones. The mechanical means of doing this I do not here describe for 50 the reason that they are features of the invention for which I have applied for Letters Patent Serial No. 186,459, filed April 25, 1927, as aforesaid.

While I may regulate and control the with- 55 drawal of products from the several zones of the dephlegmator by hand operated valves or other like means, I prefer to operate, regulate and control the withdrawal of products from the dephlegmator by suitable thermostatic 60 means, using any one of the thermostatic devices known and used in the arts that may be adapted to the purpose. Having determined the heat ranges of any desired series of products I can thus automatically separate and withdraw them.

The descriptive outline I have given above of the particular means of dephlegmating and separating is not intended to limit in any manner my invention either of process or apparatus, but merely to indicate effective 70 means of operation.

I have found that certain constituents of lubricating oil as ordinarily made, other than paraffin, which are easily cracked raise the pour test of the oil. These constituents, 75 which are detriments rather than aids to lubrication, I remove during pre-treatment performed as described, and in this manner I produce a lubricating oil with a lower pour test.

I may use my colloidal addition agent in a dry form, but I prefer to wet it with water. I find that water thus used is itself substantially in effect a colloidal addition agent. Water when added to hot oil by itself in any appreciable quantity cools the oil and tends to halt and temporarily hinder reactions, but water distributed over the surface of a solid finely divided addition agent when added to hot oil is practically instantly evaporated 85 and transformed to nascent steam and materially aids the reactions taking place in the oil. Just how it does this is not entirely clear, but it seems demonstrable that there is some disassociation of water molecules that provides hydrogen for the production of desirable fractions and some oxidization effects that are beneficial. Water so added, that is, on the surface of a solid colloidal addition agent, I find to be very different in its action 90 from introduced steam and much more efficient in producing desirable results.

I claim:

1. Apparatus for the production of lubricating oils comprising a vaporizing chamber 100 containing a plurality of distribution plates to provide extensive evaporation surfaces, means for introducing oil stock and dispersed adsorptive agent thereinto, means for inducing repeated circulation of said material through a heater, means for introducing adsorption addition agent into the circulating material before same passes through the heater, means for withdrawing disassociated carbon and sediment from the vaporizing chamber, a mechanical agitator within said chamber, a dephlegmator in open communication with the vaporizer, said dephlegmator having a series of separately communicating progressively cooler zones, and suitable means 110 for the withdrawal of products separated from any of said zones, and means for creating a vacuum in the dephlegmator and vaporizing chamber.

2. In an apparatus for treating liquid hydrocarbon oil, the combination of means for heating oil mixed with adsorptive addition agent under pressure, means for separating lighter products from the heated oil, means for adding an additional adsorptive agent to 120

the residual oil, means for heating, distilling and condensing said residual oil while subjected to vacuum, and means in the distilling means for mechanically agitating liquid oil and adsorptive addition agent, and means for withdrawing unvaporized oil.

3. Apparatus for the production of lubricating oils comprising a vaporizing chamber containing a plurality of distributing plates to produce extensive evaporation surfaces, means for producing circulation of oil over said surfaces, a heated coil for heating said oil, means intermediate the means for producing circulation and the heated coil for introducing adsorption addition agent into the circulating oil, means for withdrawing dissociated carbon and sediment from the vaporizing chamber, a dephlegmator in open communication with the vaporizer, said dephlegmator having a series of separated communicating progressively cooler zones, and suitable means for the withdrawal of products separately from any one of said zones, and means for creating a vacuum in the dephlegmator and vaporizing chamber, the oil and adsorptive agent being repeatedly circulated from the lower portion of the vaporizing chamber over the uppermost evaporation plate where it passes by gravity down over the other plates and back to the body of oil in the lower portion of the chamber.

In testimony whereof, I have hereunto set my hand this 24th day of August, 1928.
